UNITED STATES PATENT OFFICE

159,625

FLATIRON CORD HOLDER

Leonard Johnson, Chicago, Ill.

Application December 17, 1949, Serial No. 6,697

Term of patent 14 years

(Cl. D49—6)

To all whom it may concern:

Be it known that I, Leonard Johnson, a citizen of the United States of America, residing at Chicago, in the county of Cook, and State of Illinois, have invented a new, original, and ornamental Design for a Flatiron Cord Holder, of which the following is a specification, reference being had to the accompanying drawing, forming a part thereof.

In the drawing, Fig. 1 is a side elevational view of a flatiron cord holder showing my new design; and

Fig. 2 is an enlarged front elevational view of the upper portion of Fig. 1.

The rod portion is broken in Fig. 1 and fragmentarily shown in Fig. 2 for convenience of illustration.

I claim:

The ornamental design for a flatiron cord holder, as shown.

LEONARD JOHNSON.
